REFRIGERATOR CAR DOOR AND THE LIKE

Edward A. Sweeley, Alexandria, Va., and Norman T. Anderson, Washington, D. C.

Application July 29, 1932. Serial No. 626,128

5 Claims. (Cl. 20—35)

Our invention relates to refrigerator cars, and more particularly to refrigerator car doors, although susceptible for use in other doors. It has among its objects to provide effective, practically 5 air-tight sealing joints to the doors.

To the accomplishment of the foregoing and such other objects as may hereinafter appear, the invention consists in the features hereinafter particularly described and then sought to be 10 clearly defined by the claims, reference being had to the accompanying drawings forming a part hereof, and illustrating the preferred embodiment of the invention, and in which:

Figure I shows a front elevation of a refrigerator car door, in closed position, and formed with rounded top corners;

Figure II is a horizontal cross-section taken about mid-way between the bottom and top of a door proper, showing beveled and offset door posts and stiles, with the door in closed position and with the packing material at the joints omitted, for clearness of illustration;

Figure III is a vertical section through the center line of a door, showing the beveled and offset door header and door top cross rail, with the door in closed position;

Figure IV is a vertical section through the door top rail and door header, showing the beveled and offset portions of the rail and header on an enlarged scale and provided with padding;

Figure V is an enlarged horizontal section through the door center stiles, with the beveled and offset portions provided with padding;

Figure VI is an enlarged horizontal section through a side stile of the door and a door post, with padding applied.

The door is made in sections, and the letter A indicates one section which will be referred to as the male section, and B the companion section, which will be referred to as the female door or section. The numeral 1 indicates the door posts of the two door sections, 2 the header for the doors, and 3 the threshold for the doors. The doors are hinged to their respective posts by 45 suitable hinges 4. The female door B has a metal plate 5 applied at its lower end to form a bearing for a stop lip 6 which is pivotally secured to the threshold 3 so as to be swung upward against the plate 5 when the door B is closed and functioning in positioning and holding it closed. The female door B is provided near its upper end with a metal lip 7 that will lap over onto the door header 2 when the door is closed. The upper outer corners of the door sections are rounded as at 55 so as to form tight fitting corner joints, the

rounded portions extending from front to rear of the door sections.

As illustrated in Figure II, each door or door section has an outer stile 9; the male door A has an inner stile 10, and the female door B has an inner stile 11. The doors including the outer end and inner stiles are covered on the outside by sheathing 12, which may be grooved or corrugated vertically, and covered on the inside by a boarding or lining 13.

The door posts 1 have their faces next toward the door end stiles 9, and the adjoining end stiles 9 of the door sections next towards the end posts, rabbed, with the result that the faces of the door posts towards the end door stiles are formed with faces 19 and 18 extending respectively in the direction of the outer and the inner faces of the door sections, and connected one to the other by a face 14 extending substantially at right angles to the direction of faces 19 and 18 and in the direction of the width of the door, and the rabbet of the end stile of the door forming faces 23 and 24, extending towards the outer and inner faces of the door, respectively, and connected by a face 15 extending substantially at right angles to the direction of faces 23 and 24, and in the direction of the door width, as illustrated in Figures II and VI of the drawings. The face 14 of the door posts serves as a seat for a relatively soft pad 16, of suitable material, (Figure VI) which

extends the full length of the face 14 from top to bottom of the post and is secured in place by nails 17. A strip or sheet of canvas 20 covers the padding 16 and also faces 18 and 19 of the rabbed face of each end post, from top to bottom of the post, and has its opposite ends folded and lapped upon itself, as indicated at 22 in Figure VI of the drawings, so as to provide smooth folded edges to the canvas at the outer and inner faces of the door, as illustrated in Figure VI of the drawings, the canvas being held in place by nails 21 passing through it and into the post, as indicated in the drawings.

The canvas practically fills the clearance between the opposite disposed faces of the door posts and outer end stiles of the door, and the canvas plus the padding 16, along the faces 14 and 15 of the door posts and end stiles provide an additional thickness at those points so that when the door is closed, the padding is compressed and a tight joint formed. The surfaces 23 and 24 of the door stiles 9 bear lightly against the canvas, covering surfaces 18 and 19 of the door posts 1, and the point of greatest compression is between the surfaces or faces 15 of the stiles 9 and sur-

110

faces 14 of the door posts, against which the padding 16 is seated, and thus a very effective sealing joint is provided between the end stiles of the door and the door posts.

5 The male door A is provided with a center stile 10 beveled at 25 and 26 towards the outer and inner faces of the door, respectively, and joined at their inner ends by a substantially straight surface or face 27 extending in the direction of the 10 width of the door, and substantially at right angles to the beveled surfaces 25 and 26. The center stile 11 of the section constituting the female door B is beveled at 28 and 29 extending in the direction of the outer and inner faces of the door, 15 respectively, and connected at their inner ends by a surface or face 30 extending in the direction of the width of the door and substantially at right angles to the beveled faces 28 and 29. The face or surface 30 serves as a seat for a 20 padding 31 made of suitable soft material and secured by nails 32. This padding 31 extends from bottom to top of the door. The beveled surfaces 28 and 29, as well as the padding 31, are covered by a strip or sheet of canvas 33, which extends 25 from top to bottom of the door, and held by nails 34 driven into stile 11. At opposite ends, the strip or sheet of canvas 33 is folded and lapped inwardly, as indicated at 35, at the front and rear 30 of the door and secured in place by nails similar to nails 34. The padding 31 on the surface 30 lies opposite to the surface 27 of the door center stile and when the door is closed, the padding 31 is compressed by the surface 27 of stile 10 and a tight seal effected. The surfaces 25 and 26 of 35 stile 10 contact comparatively lightly against the canvas over the bevels 28 and 29 of the female center stile 11 when the male door is closed, while the greatest compression will be exerted against padding 31 opposite to surface 27 of the male door 40 stile 10, as indicated in Figure V.

In Figure III of the drawing the threshold 3 of the door is beveled as usual, and there will be used customary weather-stripping at rear of the door lining against the floor 36 at 37, but not 45 illustrated because not claimed as a part of the invention. The door has a bottom rail 38 to each door section, and also a top rail 39. In the present instance the top door rail 39 is formed with a beveled or inclined face or surface 40 extending 50 inwardly and downwardly from the front of the rail and at its rear there is formed a vertical depending wall or face 42 from the lower end of which there extends inwardly and downwardly, towards the rear face of the door, an inclined or 55 bevel surface or face 41. Over the top stile of the door, extending from front to rear of the door, is placed a covering plate 43, preferably of sheet zinc. At the front of the top rail of the door, the plate is formed with a depending flange 44 which 60 may extend outside of the door sheathing 12 and secured by nails, 45. The plate 43 at its rear end is formed with a downwardly extending flange 46 which enters a correspondingly formed recess or 65 groove in the rear lining board 13 of the door and is secured by nails 48. At the point where the rear flange 46 of plate 43 enters the groove in the lining board 13 a suitable water-proof cement 70 may be applied to form a tight and water-proof joint. The door header 2 (see Figure IV) is formed at its under face with a bevel or rearwardly and downwardly inclined surface or face 49, from the rear of which extends downwardly a vertical surface or face 51 and from the lower end of that surface there is a rearwardly and downwardly inclined or bevel surface 50. The vertical 75

surface 51 is covered with a suitable soft padding 52 secured by nails 53 and extending substantially the entire width of the surface against which it is seated.

The bevel surfaces 49 and 50, and also padding 52, are covered or faced with a canvas sheet or layer 54, the ends of which are folded and lapped as indicated at 55 and 56, and secured by nails 57 driven through the canvas and into the header 2. At the inner side or face of the door header, there is attached in line with the inclined or bevel surface 50, a weatherstripping consisting of a rope 58, or other suitable material, confined in the fold of a piece of canvas 59, and secured to the header by nails as illustrated in Figure IV, so as to insure an air-tight seal at such point. This is additional to the seal resulting from compression of pad 52 by pressure of surface 42 of the door top rail 39 and contact of bevel surfaces 40 and 41 of the top door rail 39 against canvas 54, which occupies the clearance between the adjacent faces of the door top rail and the door header.

We have illustrated and described with particularity the preferred details of the various parts, but there may be changes made in the details and essential features be retained.

The disposition of the faces or surfaces of rabbeted portions of the stiles and end posts and of the door top rails and door header contribute 105 to make most efficient seals at the joints and also promote ease in movement of some parts relatively to other parts with the minimum of friction and wear without detracting from the efficiency of sealing at the points of contact at the 110 joints; and the positioning of the cushion pads and degree of compression against them produce maximum sealing effect between the rabbeted faces of the members.

Having described our invention and set forth 115 its merits, what we claim is:

1. A door including upright end posts and upright end stiles having their adjacent faces rabbeted to form oppositely disposed off-set portions, spaced one from the other, a cushion pad applied to a face of one of the off-sets of the door posts and extending substantially from top to bottom of the door, and canvas extended across the face of said cushion pad and continued over the outwardly extending faces of the rabbeted 125 portions of the posts toward the outer and inner faces of the door, said canvas having its opposite ends lapped where it lies between the rabbeted faces of the end posts and door stiles, at 130 opposite sides of the door, and presenting outwardly exposed folds of the lapped canvas at opposite sides of the door, said canvas being secured to the door posts.

2. A door formed of two sections, the sections provided with upright meeting stiles, the adjacent faces of the stiles being rabbeted to form offset portions, each having outwardly extending bevel faces, one extending in an opposite direction to the other, and connected together at their inner ends by a face extending substantially at right angles to the outwardly extending bevel faces, the rabbeted face of one stile being spaced from the rabbeted face of the adjacent stile, a cushion pad seated on an intermediate connecting face of one stile and 140 extending substantially from top to bottom of the door, and canvas extended across the face of said cushion pad and continued over the outwardly extended bevel faces of the rabbeted face of the stile, and secured to the stile, said canvas 145 150

occupying the clearance between the rabbeted faces of the adjacent stiles.

3. A door provided with a top cross rail having a top surface for a distance inclined rearwardly and downwardly from the front towards the rear of the door and then extended for a distance downwardly towards the bottom of the rail and thence rearwardly and downwardly towards the rear of the door, and a metallic facing applied to the top surface of the rail and formed at each end with a downwardly extending flange, the flange at the rear fitting in a recess formed in an inner lining to the door.

4. A door header having its under face for a distance inclined from front towards its rear, thence downwardly towards the bottom of the header to form a seat for a cushion pad, and thence on a downward incline towards its rear, a cushion pad applied to said seat, and canvas covering the cushion pad and continued over the inclined surfaces which extend respectively towards the front and rear of the door, said canvas being secured to the header.

5. In a door including a top cross rail and a header; the rail and the header having their adjacent faces formed each for a distance with rearwardly and downwardly inclined surfaces, thence with a downwardly extending intermediate surface, and thence with rearwardly and downwardly inclined surfaces, a cushion pad seated upon the intermediate downward extended surface of the header, and a canvas covering the cushion pad and continued over both of the downward-rearwardly inclined surfaces of the header, said canvas being secured to the header and occupying a clearance between the adjacent faces of the header and door cross rail, the canvas being lapped to form a fold at the front of the header and rail, and a flexible strip enclosing a core of suitable material and applied to constitute a seal at the joint between the header and the cross top rail at one side of the door.
